UNITED STATES PATENT OFFICE.

LESTER P. CLARK, OF FANWOOD, NEW JERSEY, ASSIGNOR OF ONE-HALF TO ANTHONY L. STEBOR, JR., OF PLAINFIELD, NEW JERSEY.

MONKEY-WRENCH.

1,308,840.

Specification of Letters Patent.

Patented July 8, 1919.

Application filed February 8, 1919. Serial No. 275,741.

To all whom it may concern:

Be it known that I, LESTER P. CLARK, a citizen of the United States, and residing at Fanwood, county of Union, and State of New Jersey, have invented certain new and useful Improvements in Monkey-Wrenches, of which the following is a clear specification and illustrated in the annexed drawings.

10 The particular novel features are pointed out in the annexed claims.

My invention relates in general to a type of monkey wrench in which the adjustment of the movable jaw is accomplished by releasing the jaw from the shank and by sliding it in to the desired position where it can be conveniently locked by a short twist of the wrench handle.

Referring to the drawings, Figure 1 is a 20 side view of my improved wrench partly in section. Fig. 2 is a top view thereof. Fig. 3 is a transverse section on the line III III in Fig. 1 seen in direction of the arrows, and Fig. 4 is a detailed perspective view of the 25 member which locks the movable jaw in position.

Referring to Fig. 1, 1 is a rectangular shaped shank, at the outer end of which is fixed the stationary jaw 2 of the wrench. 3 30 is a movable jaw slidably disposed on shank 1, and 4 is a key slightly longer than the shank and embedded therein in a groove 5 as shown in Figs. 1, 2 and 3. The rear end of key 4 protrudes slightly beyond the rear 35 end of the shank and has its under side tapered as shown at 11 in Figs. 1 and 4. To the rear end of shank 1 is threaded handle 7 by means of a threaded bushing 8 which extends into the handle 7 and is fastened there- 40 to by riveted pin 10. The outer end of bushing 8 is formed into a tapered head 9 and of such form that it will engage the tapered portion 11 of key 4 when the handle is screwed entirely on to the shank 1 as shown 45 by the dotted lines in Fig. 1.

So long as the handle is slightly unscrewed from the shank as shown in full lines in Fig. 1, key 4 lies flat in its groove 5 in the shank and permits the sliding of 50 the movable jaw 3 freely on the shank. The upper face of key 4 preferably serves as a bearing surface together with the shank for

the movable jaw. After the jaw has been moved into the desired position on the shank, the handle is entirely screwed down 55 on to the shank so that head 9 of the handle engages the beveled portion 11 of key 4 thereby lifting its rear end out of the groove which causes the movable jaw 3 to jam on the shank so that it is locked thereto. 60

The great advantage of this construction is that the locking and unlocking of jaw 3 can be effected without releasing the grip on the handle, which is particularly convenient at such occasions where the other hand of 65 the operator is engaged in holding parts of machinerv.

What I claim is:

1. A wrench of the character described having a shank, a jaw fixed at one of the 70 shank ends and a movable jaw slidably disposed on the shank, a jamming member extending over the length of the shank and being embedded therein, and means at the handle end of the wrench for lifting the rear 75 end of the jamming member to lock the movable jaw on the shank at the desired place.

2. In a wrench of the character described, having a shank, a jaw fixed at one of the shank ends and a movable jaw slidably 80 disposed on the shank, a jamming member extending over the length of the shank and embraced by the sliding jaw, a handle having screw-threaded engagement with the shank, the jamming member and the handle 85 having engaging surfaces of wedge form, whereby on turning the handle, the jamming member may be moved laterally at its end adjacent the handle to fix or release the 90 movable jaw.

3. A wrench of the character described having a shank, a jaw fixed at one of the shank ends and a movable jaw slidably disposed on the shank, a jamming member extending over the length of the shank and 95 being embedded therein and forming part of the sliding surface for said movable jaw, a handle threaded on to the rear end of the shank and having a lifting head adapted to engage and lift the rear end of the jamming member when the handle is screwed toward the jaws to lock the movable jaw on the shank at the desired place.

LESTER P. CLARK.
